(57) **CLAIM**

The ornamental design for a removable memory card for use with portable electronic devices, as shown.

DESCRIPTION

FIG. 1 is a top, front and left side isometric view of a removable memory card for use with portable electronic devices of the new design;

FIG. 2 is a top, bottom and left side isometric view thereof;

FIG. 3 is a top plan view thereof;

FIG. 4 is a left side elevational view thereof;

FIG. 5 is a front elevational view thereof;

FIG. 6 is a bottom plan view thereof;

FIG. 7 is a right side elevational view thereof; and,

FIG. 8 is a rear elevational view thereof.
